UNITED STATES PATENT OFFICE.

LUDWIG BENDA, OF MAINKUR, NEAR FRANKFORT-ON-THE-MAIN, AND OTTO SIEVERS, OF FECHENHEIM, NEAR FRANKFORT-ON-THE-MAIN, GERMANY, ASSIGNEES TO I. G. FARBEINDUSTRIE AKTIENGESELLSCHAFT, A CORPORATION OF GERMANY.

BENZOXAZOLON ARSONIC ACIDS.

No Drawing. Application filed July 27, 1925, Serial No. 46,500, and in Germany August 11, 1924.

We have found that according to the process described in United States Patent 1,539,798 benzoxazolon-6-arsonic acids of the general formula:

according to the above process.

We have now found that the nitrobenzoxazolones (IV) obtained by the action of phosgene on 1-hydroxy-2-amino-4-nitrobenzol and its derivatives (III) can be reduced (V) subsequent diazotizing and treatment with arsenites (VI) be converted into compounds of formula II and that surprisingly the benzoxazolon-ring remains intact during all these operations. For instance:

The result or substances valuable as therapeutics and of importance moreover as intermediates for the production of other pharmaceutical preparations.

The process is carried out in a simple manner. The parent materials, the 4-nitro-2-aminophenols formed by the partial reduction of the 2,4-dinitrophenols, are available in any quantity.

Example 1.

5-nitrobenzoxazolon.—15.4 kg. 4-nitro-2-aminophenol are dissolved in 300 liters water and 10 l. caustic soda solution 38° Bé.

On cooling the amino benzoxazolon crystallizes from the filtrate as faintly violet needles. It is practically insoluble in naphtha, benzene and ether, but dissolves more readily in alcohol and easily in acetone. It is soluble in hot water. In dilute alkalies the solution which may easily be prepared and, on allowing to stand assumes a deep color. The diazo solution coupled with resorcinol is yellow-red and with R-salt red-violet.

Benzoxazolon-5-arsonic acid.—3.5 kg. 5-aminobenzoxazolon are dissolved in 20 liters water and 2 liters caustic soda solution 38° Bé., 2.6 liters nitrite solution (of which 130 cc.=1000 nitrite) and 28 kg. ice added and finally diazotized with 6 liters hydrochloric acid.

The diazo solution is gradually added to a solution of 45° of 6.4 kg. sodium arsenite and 9 kg. sodium carbonate in 40 liters water. When all has been added and the liquid does not any longer contain a diazo compound it is acidulated and rapidly decanted by suction. After standing for some length of time and cooling the arsonic acid is precipitated from the filtrate in the shape of yellow-brown crusts which may be recrystallized from a hot sodium acetate solution or boiling water then forming colorless crystals. In alkalies they dissolve easily cold. In the customary organic solvents they dissolve sparingly or are insoluble.

7-methyl-5-nitrobenzoxazolon.—The 5-nitro-3-amino-2-hydroxy-1-methylbenzol obtained by the reduction of dinitrocresol with sodium disulfide is dissolved in 500 liters water and 80 liters caustic soda solution 40° Bé. and phosgene added. 40 liters caustic soda solution are added until the nitroaminocresol is used up, and the solution is then decanted by suction. The nitromethylbenzoxazolon thus obtained may easily be reduced. It dissolves in glacial acetic acid, alcohol, acetone and ether, is sparingly soluble in hot water, but dissolves readily in dilute alkalies forming alkali metal salts in the form of crystalline yellow needles. The melting point is 236–237° C.

50

7-methyl-5-aminobenzoxazolon.—9 kg. 7-methyl-5-nitrobenzoxazolon are gradually added to a boiling suspension of 11 kg. iron filings in 40 liters water and 1.5 liters acetic acid 50%. After complete reaction it is made up to 80 liters rendered alkaline while boiling hot with 2.5 kg. sodium carbonate

solution and decanted by suction. On cooling, the aminomethylbenzoxazolon crystallizes from the filtrate as faintly violet colored needles. It dissolves readily in dilute acids and alkalies. The diazo solution coupled with R-salt is red-violet and with resorcinol yellow-red. It is practically insoluble in ether benzene, naphtha, dissolves in hot water and alcohol and very readily in acetone. On standing the alkaline solution quickly takes on a dark color.

7-methylbenzoxazolon-5-arsonic acid.—3.8 kg. 4-methyl-6-aminobenzoxazolon are mixed with 4 liters water and 12 kg. ice, adding 4 liters hydrochloric acid 38%, this is then diazotized with 2.6 liters nitrite solution (130 cc.=1000 NN). To the diazo solution 6.4 kg. sodium arsenite are added while stirring well, which is then rendered slightly alkaline by adding with care about 5 kg. sodium carbonate solution. The solution is stirred until a diazo compound cannot be found any longer. It is then acidulated and immediately decanted by suction. After standing for some length of time the arsonic acid is precipitated as brown crusts which may be refined from sodium acetate solution or their sodium salt, then forming colorless crystals readily soluble in alkalies and sparingly so in cold water. In the customary organic solvents the 7-methylbenzoxazolon-5-arsonic acid is insoluble.

*Example 3.*100

105

7-chloro-5-nitrobenzoxazolon.—The 5-nitro-3-amino-2-hydroxy-1-chlorobenzene obtained by the reduction of 132 kg. dinitrochlorophenol with sodium disulphide is dissolved in 500 liters of water and 80 liters of caustic soda solution 40° Bé. Phosgene is passed into the blood-red solution gradually adding 40 liters caustic soda solution until the chloronitroaminophenol is used up. The precipitated chloronitrobenzoxazolon is decanted by suction and may be reduced immediately.

It dissolves in acetic acid, acetone, ether, and alcohol, sparingly so in hot water, benzene, but readily in dilute alkalies, forming alkali metal salts as yellowish crystalline needles. Melting point 210–211° C.

7-chloro-5-aminobenzoxazolon.—9 kg. 7-chloro-5-nitrobenzoxazolon are gradually entered into a boiling suspension of 11 kg. iron filings in 40 liters water and 1.5 liters acetic acid 50%. After complete reduction the solution is made up to 80 liters rendered alkaline while boiling hot with 2.5 kg. sodium

carbonate solution and decanted by suction. The aminomethylbenzoxazolon crystallizes on cooling in the form of faintly colored needles. It dissolves in hot water, alcohol and acetone, is however practically insoluble in ether and benzene. It dissolves readily in dilute acids and in alkalies. Its alkaline solution rapidly becomes dark colored. Its diazo solution coupled with R-salt is bluish-red and with resorcinol orange.

7-chlorobenzoxazolon-5-arsonic acid.—4.3 kg. 7-chloro-5-aminobenzoxazolon are mixed with 4 liters water and 4 liters hydrochloric acid 38% and 12 kg. ice added. The solution is diazotized by the addition of 2.6 liters nitrite solution. (130 cc.=1000 NN). 6.4 kg. sodium arsenite are added while stirring well and the solution is rendered slightly alkaline by adding with care about 5 kg. sodium carbonate solution. This is stirred until a diazo compound cannot be demonstrated any longer. It is then acidulated and decanted by suction. After standing for some length of time the arsonic acid is precipitated as brown crusts. It may be purified over its sodium salt and then forms white crystals easily soluble in alkalies, sparingly so in hot water and insoluble in cold water. In the customary organic solvents the 7-chloro-benzoxazolon-5-arsonic acid is insoluble.

Having now particularly described and ascertained the nature of our said invention and in what manner the same is to be performed, we declare, that what we claim is:

1. Process for the production of benzoxazolon-5-arsonic acids by allowing phosgene to act on aryl-1-hydroxy-2-amino-4-nitro-compounds, by reducing the 5-nitroaryloxazolons, thus formed, and transforming these amino compounds into the corresponding arsonic acids in the customary manner.

2. As new product the 7-chlorobenzoxazolon-5-arsonic acid of the formula:

forming colorless crystals, easily soluble in alkalies, sparingly soluble in hot water, insoluble in cold water and in the customary organic solvents.

In witness whereof we have hereunto signed our names this 14th day of July, 1925.

LUDWIG BENDA.
OTTO SIEVERS.
